(57) **CLAIM**

The ornamental design for an insulated box, as shown and described.

DESCRIPTION

FIG. 1 is a top front perspective view of an insulated box showing our new design in an open configuration;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is a top front perspective view of an insulated box showing our new design in a closed configuration;

FIG. 9 is a front view thereof;

FIG. 10 is a back view thereof;

FIG. 11 is a right side view thereof;

FIG. 12 is a left side view thereof;

FIG. 13 is a top view thereof; and,

FIG. 14 is a bottom view thereof.

The broken lines shown in the figures illustrate portions of the insulated box that form no part of the claimed design.

1 Claim, 12 Drawing Sheets
